(57) **CLAIM**

The ornamental design for a mobile phone shell, as shown and described.

DESCRIPTION

FIG. 1 is a front perspective view of a mobile phone shell, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof with an environmental mobile phone; and,

FIG. 10 is a rear perspective view thereof with an environmental mobile phone.

The broken lines in FIGS. 9 and 10 form no part of the claimed design; they depict an environmental mobile phone that forms no part of the claimed design.

1 Claim, 10 Drawing Sheets(56)
